MEANS FOR PREPARING IGNITIBLE MIXTURES

Hermann Teegen, Bunde, Westphalia, Germany,
assignor to Lohmann-Werke A. G., Bielefeld,
Germany, a corporation of Germany

Application June 21, 1949, Serial No. 100,479

7 Claims. (Cl. 123—119)

1

The present invention relates to a method of and means for preparing an ignitable mixture for internal combustion engines. The conventional manner to prepare and feed an ignitable mixture to an internal combustion engine requires either a carburetor atomizing the fuel by means of nozzles in co-operation with an air current when the engine operates according to the Otto principle, or an injection pump charging fuel under high pressure into the combustion chamber is needed when the diesel principle is applied. Both carburetors and injection pumps are highly complicated mechanisms which are frequently subject to disturbances.

The invention aims therefore to provide a new method and means whereby an ignitable mixture of air and fuel can be obtained in an extremely simple manner and without requiring the application of high pressure in the preparation of such mixture which, depending on the type of engine, charged with it, may be ignited either by means of a conventional spark plug, or by self-ignition due to compression, or by other suitable and conventional means.

The invention essentially consists in that air admitted into a casing is vehemently agitated therein by a movable member which also breaks up simultaneously admitted liquid fuel into particles and thoroughly mixes such particles with the agitated air, wherein the quantity of the fuel in proper relation to the air may be adjusted by any suitable and conventional valving means in the path of the fuel and/or air to the casing.

The invention also contemplates heating of the so obtained mixture on its way from the casing to its place of use in order to promote the evaporation of the liquid particles, and, if it is intended to use the mixture e. g. in an engine operating according to the diesel principle, to attain self-ignition at a lower pressure than would be required with a cold mixture.

Another object of the invention is to make use of the crank rotating in the crank case of an engine of the reciprocating type as a means for preparing an ignitable air and fuel mixture.

Further objects and details of the invention will be apparent from the description given hereinafter and the accompanying drawings showing several embodiments thereof by way of example. In the drawing

Fig. 1 is a longitudinal cross-section of an embodiment of the invention applied to an internal combustion engine of the reciprocating type,

Fig. 2 is a cross-section along line 2—2 of Fig. 1,

Fig. 3 is a longitudinal cross-section of another embodiment,

Fig. 4 is a cross-section along line 4—4 of Fig. 3,

2

Figs. 5 and 6 are views similar to Figs. 3 and 4 respectively of a modification, and

Fig. 7 is a cross-section of still another embodiment.

5 As stated hereinbefore the method according to the invention comprises admitting air and a liquid fuel into a casing, vehemently agitating the air and simultaneously breaking up the liquid fuel into particles and mixing the latter with the 10 agitated air with the aid of a member rapidly moving within the casing. The breaking up of the liquid fuel will be facilitated, if care is taken that the liquid fuel reaches the casing in form of drops rather than in a continuous stream. 15 However, this is not necessarily so, as it is more or less merely a question of the form and speed of the movable member which is decisive of the time required to break up the coherence of the liquid. In order to obtain an ignitable mixture 20 it is of course necessary that the quantity of fuel in relation to the quantity of air is within the limits between which the mixture will be inflammable. The method is not restricted to any particular kind or composition of liquid fuel. Gasoline, light and heavy fuel oils, and liquid fuel mixtures of various chemical composition, fluidity and viscosity can be used. In fact, I have found that all the various fuels I have tested and which are conventionally used in the operation 25 of internal combustion engines can be successfully treated by my method. It is even possible, as I have found in tests, to prepare ignitable mixtures, one after the other, of very different liquid fuels with the same apparatus.

30 Embodiments of apparatus for the indicated purpose will now be described with reference to the drawing. The apparatus is shown in connection with two-stroke engines; however, it is to be understood that this is not done by way of limitation but that the method and means according 35 to my invention may be advantageously used with other kinds of internal combustion engines too. Figs. 1 and 2 illustrate, in a diagrammatical form, a two-stroke motor in general denoted by 10 to which the apparatus in general denoted by 11 for preparing an ignitable mixture is attached. The motor comprises the cylinder 12 mounted on the two-partite crankcase 13. The piston 14 acts via the piston rod 15 on crank 16 with shaft 17 journalized in bearings 18 in the crankcase 13, and 40 controls with its upper edge 19 an inlet port 20 and an outlet port 21 as it is conventional in certain types of two-stroke-engines. The space 22 between the piston 14 and the cylinder head 23 constitutes the combustion chamber. It is immaterial from the view point of the invention, whether ignition is to be caused by high compression in this engine or by means of spark plugs.

or other conventional means none of which are shown for that reason. Attached to the one side of the crankcase 13 by means not shown, there is a housing extension 24 into which a reduced end 25 of the crank shaft 17 projects. A toothed wheel 26 is secured to the shaft end 25 for common rotation. The housing 24 has an inlet socket 27 and an outlet socket 28, the latter being connected by a pipe 29 to the cylinder inlet port 20. The inlet socket 27 comprises two branches 30 and 31. Branch 30 serves for the admission of air to housing 24 whereas branch 31 is adapted for connection to a source of liquid fuel supply. Valving means, e. g. such as shown in the embodiment of Fig. 7 may be applied to control the passage of air and fuel to the housing 24 in order to adjust the relative quantities. To the other end 32 of the crank shaft 17 a gear wheel 33 is secured from which motor power may be derived, and which may be rotated by exterior means in order to start the motor.

The device operates in the following manner: When crank shaft 17 rotates in the direction of the arrow in Fig. 2, the toothed wheel 26 will be taken along. Fuel entering through the socket branch 31 either by gravity feed or supplied by a conventional pump will splash on the periphery of the wheel 26 where the sharp edged teeth, owing to the rotation, will break up the liquid into particles. Simultaneously, the air entering the housing 24 through socket branch 30 will be vehemently agitated and an ignitable mixture of liquid particles and agitated air will be produced if the ratio of fuel to air is kept within the limits of inflammability. Whenever, then, during the reciprocation of piston 14 the inlet port 20 is open, quantities of such ignitable mixture will pass from the housing 24 through the socket 28, pipe 29, inlet port 20 into the combustion chamber where it may be ignited to drive the motor.

A simplification of the structure and other advantages of the means for preparing an ignitable mixture can be attained if the mixture is for use in an internal combustion engine of the reciprocating type where a substantially closed crankcase is provided or the crankcase can be closed except for such ports or ducts as will be described in connection with the embodiment illustrated in Figs. 3 and 4. In such a case, the crankcase can be used as the casing in which the mixture will be prepared, and the crank as the movable member causing the agitation of the air, the breaking up of the fuel and the intermixing. The motor in Figs. 3 and 4 comprises the cylinder 40, divided crankcase 41, crank shaft 42, counterweighted crank 43, crank pin 44, piston 45 and piston rod 46, all in the conventional arrangement. The crankcase space 47 communicates with the cylinder space 48 underneath the piston 45 whereas the space 49 above the piston constitutes the combustion chamber. No means for igniting a fuel mixture are shown for the reasons stated in connection with Figs. 1 and 2. Nor is the conventional exhaust port of the cylinder visible in the illustrations of Figs. 3 and 4. The cylinder is provided with an air inlet port 50 and a fuel inlet port 51, both under the control of the bottom edge 52 of the piston 45. As stated hereinbefore, the ducts for admitting air and fuel, or at least one of them, may be provided with valving or other means for adjusting the quantities admitted. The cylinder is also provided with a groove 53 which constitutes a duct from the combined spaces 47 and 48 to the combustion chamber 49, and which is under the control of

the upper piston edge 54. It is to be noticed that in the cross-section Fig. 4, in order to avoid overcrowding of the illustration, only the cylinder 40 with fuel duct 51, groove 53 and a bottom flange 55 has been shown, which latter serves for the attachment of the cylinder to the crankcase 41.

This embodiment operates in the following manner: While the crank shaft 42 rotates, air and fuel can enter the combined spaces 47 and 48 through the inlet ports 50 and 51, respectively, as long as during the reciprocation of the piston, the lower edge 52 is above these ports. The air will fill the mentioned spaces and will be agitated by the crank and counterweight 43. Simultaneously the admitted fuel will splash on the crank and will be broken upon into particles and thoroughly mixed with the air. In this process the variation of pressure caused by the reciprocating piston is of assistance. It is also helpful, if sharp edges such as the edges 56 are provided, although I have obtained satisfying results even if there are no such edges. Now, when the piston on its downward stroke frees, with its upper edge 54, the upper end of the groove 53, quantities of the mixture prepared will pass from the combined space 47, 48 to the combustion chamber 49 through the duct formed by the groove 53 and the outer surface of the piston. The arrangement of this duct between the cylinder and piston walls is advantageous because these walls are heated by the combustion in chamber 49 and therefore communicate heat to the mixture during its passage through the duct. As stated hereinbefore, such heat will aid in the evaporating of the liquid particles.

The device shown in Figs. 5 and 6 is very similar to that just described. It mainly differs from the latter in the arrangement of the inlet ports for the air and fuel and of the duct between the mixing spaces and the combustion chamber. In this case, an air conduit 60 and a fuel conduit 61 are provided in the upper part of the cylinder 62. Both conduits end in a transverse bore 63 which opens into the cylinder space at 64 whereas its outer end is closed by a cover 65. The port 64 is controlled by the lower edge of piston 45. With this arrangement, air and fuel will be admitted during the same length of time or length of portion of the reciprocating cycle, whereas in the precedingly described structure the time for admitting the fuel is shorter than that for the air. The duct 66 between the lower cylinder space 48 and the combustion chamber 49 is provided entirely within the wall of the cylinder 62 which is heated by the combustion in that chamber. Its port 67 is under the control of the upper edge 54 of the piston. It is to be noticed that there is a sharp edge 68 at the lower end of the duct 66. This edge is provided also for the purpose of creating eddies, i. e. of more thoroughly intermixing the fuel particles with the agitated air. In order to show that the device is applicable to engines with an ignition system as well as to engines operating with self-ignition, a spark plug is indicated at 69.

The preparation of a thorough mixture of air and fuel particles can also be improved by additional means. For this purpose, the inner surface of the casing may be chromium or nickel plated, sand blasted, bonderized or treated in another manner to influence the formation of films of very small liquid particles into which the fuel is broken up as hereinbefore described and which are taken along by and intermixed with the agitated air. Another effective measure is the

provision of a plurality of sharp edged teeth on the outer periphery of the counterweight of the crank and/or on the inner periphery of the crankcase of a motor in which that case is used as the casing in which the mixture is to be prepared. Such a motor is shown in Fig. 7. The illustrated engine is of the type disclosed in my copending application Serial No. 90,619, filed April 30, 1949, and in which the fuel-air-mixture is self-ignited by high compression. This motor comprises an outer cylinder 70 secured to the divided crankcase 71. Within the cylinder a barrel 72 being closed at 73 near its top end is slidably arranged. The piston 74 reciprocates within the barrel and is operated by crank shaft 75, via crank 76 and piston rod 77. The size of the combustion chamber 78 can be varied by the adjustment of the distance of the barrel from the crank shaft axis, and such adjustment can be had by means of a screw bolt 79 in the fixed cylinder head 80 as it has been fully described in the mentioned application. The barrel space 81 underneath the piston is in communication with the crankcase space 82, similarly to the spaces 48 and 47 in Fig. 3. The barrel has an inlet port 83 and an outlet port 84 of which the port 83 is controlled by the lower piston edge 85 and port 84 by the upper piston edge 86. Port 83 is in permanent communication with a transverse bore 87 of the cylinder 70 regardless of the position of barrel 72 therein, and, for that reason is somewhat larger than bore 87. Similarly the outlet port 84 is in permanent communication with another transverse bore 88 for the escape of the exhaust gases. A member 89 is secured to the cylinder by means not shown, which member contains a conduit 90 in connection with the bore 87 and open at its other end 91 for the entrance of air. Intermediate the ends a cock valve 92 with operating lever 93 is provided whereby the passage through the conduit is adjustable. A tubular piece 94 of a narrower inner cross-section for connection to a source of a liquid fuel supply is slideable in a socket 95 which opens into the conduit 90. Piece 94 is provided with an outwardly projecting pin 96 engaged by a forked arm 97 of the lever 93. The arrangement is such that piece 94 is in its topmost position when valve 92 is fully open, and will be lowered the more valve 92 closes. Opposite socket 95, another interiorly threaded socket 98 is provided in which a screw member 99 is adjustable. This member ends in a needle point 100 which projects into the opening 101 of the piece 94, thus constituting a valve for the passage of fuel into the conduit 90. A stop nut 102 may be used to secure the needle in its adjusted position. It will be clear that with this device a very accurate adjustment of the fuel-air ratio can be attained, and that by operating lever 93 the quantities of flow of air and fuel can be simultaneously increased or reduced as may be required during the operation of the engine. However, other suitable and conventional means may be applied to adjust the supply of fuel and air to the engine.

Within the crankcase 71, the crank 76 has a sector-shaped counterweight 110 which, for the reason hereinbefore explained, is provided with sharp edged teeth 111 on its periphery. The inner periphery of the crankcase is also provided with sharp edged teeth 112 which, however, are arranged only on the sides whereas the bottom portion of the crankcase is smooth in order to prevent liquid fuel from accumulating between the teeth. A passage from the crankcase space 75

82 to the combustion chamber 78 is open through the slot or recess 113 in the barrel 72 when the upper piston edge 86 is below the upper end of the recess. The curved shape of the recess 113 is preferred to a straight one in order to create a certain current of the entering mixture in the combustion chamber as more fully explained in the mentioned application, and also to increase the length of the passage of the mixture along heated surfaces.

The device operates in a manner similar to that explained hereinbefore in connection with the embodiments shown in Figs. 3 to 6. When the motor is running air enters the combined spaces 81 and 82 through conduit 90, bore 87 and port 83 when piston edge 85 opens the latter. Simultaneously, liquid fuel drops or flows past the needle valve 96 into the conduit 90 from where it, assisted by the air current, flows on to the same spaces where it is splashed about and is broken up in particles by the rotating crank and counterweight which vehemently agitate the air and mix it thoroughly with such particles. The teeth 111 and 112 serve to increase that effect. As soon as the piston edge 86 opens the passage through the recess 113 quantities of the mixture will enter the combustion chamber in a preheated condition owing to their contact with the hot walls of the piston and the barrel. In the combustion chamber the mixture will be compressed by the piston upon its upward stroke to that pressure and, consequently, temperature at which self-ignition occurs. The effect of the preheating on the evaporation of the liquid particles on the one hand and on the lowering of the ignition pressure has been stated hereinbefore.

In the embodiments of my invention illustrated in Figs. 3 to 7, the preparation of the inflammable mixture takes place in the crankcase which communicates with the cylinder space underneath the piston. Owing to the reciprocation of the latter, the pressure in the combined spaces fluctuates. Such fluctuation or variation of the pressure is also aiding towards the desired result, that means the breaking up the fuel into very fine particles and their mixture with the agitated air. Therefore, regardless whether or not a crankcase is used as what may be called the mixing chamber, it is advisable to provide means whereby the pressure in the chamber can be caused to vary during the operation. Such means may be of any suitable and conventional kind, as for instance, a cylinder in communication with the mixing chamber and in which a piston is reciprocated in an arrangement similar to that in an engine of the type described.

It will be apparent to those skilled in the art that many alterations and modifications of the method and means herein described may be had without departure from the spirit and essence of my invention. For instance the admission of fuel and air to the casing where the mixing occurs, and/or the discharge of the mixture therefrom may be continuous rather than intermittent, or if the charging and discharging occurs intermittently the ports leading to and from the casing may be controlled by any suitable and conventional means other than the edges of a reciprocating piston. For that reason my invention shall not be limited but by the scope of the appended claims.

I claim:

1. A device for preparing an ignitable mixture for an internal combustion engine, comprising

a casing; a vent in the casing to admit air thereto, said casing having a rough inner surface to increase the formation of eddies of the air passing along said surface, a duct connected to said casing to admit liquid fuel thereto, a movable member in said casing, a driving means for said member to move it rapidly in said casing, said member, owing to its rapid movement, being a means to vehemently agitate said air in said casing, to break up said liquid fuel in particles, and to mix said particles thoroughly with said air, and another duct connected to said casing to conduct quantities of said mixture to the combustion chamber of said engine.

2. In an internal combustion engine including a crankcase, a crank rotatable therein, and a combustion chamber, the combination of means for admitting air to said case, means for admitting liquid fuel to said case, portions included in said crank and having sharp edges protruding in the space of said case, thereby to increase the agitation of the air, the breaking up of the liquid fuel into particles, and the intermixing of said particles with the agitated air, caused in said case by the rotating crank, and a conduit for the mixture from said crankcase to said combustion chamber, said conduit having sharp edges at, at least, one of its ends.

3. In an internal combustion engine including a crankcase, a crank rotatable therein and a combustion chamber, the combination of means for admitting air to said case, means for admitting liquid fuel to said case, a counterweight connected to said crank, said counterweight including sharp-edged, teeth-like projections of its periphery, and a conduit from said case to said combustion chamber for the mixture of said air and particles of said fuel produced in said casing by the rotating crank and counterweight.

4. In an internal combustion engine including a crankcase, a crank rotatable therein, and a combustion chamber, the combination of means for admitting air to said case, means for admitting liquid fuel to said case, inner sharp edged projections of said case, and a conduit from said case to said combustion chamber for the mixture of said air and particles of said fuel produced in said casing by said rotating crank.

5. A device as claimed in claim 4, said projections being provided on the lateral portions of the inner surface of said crankcase, and the bottom portion thereof being smooth.

5
10

6. In an internal combustion engine including a crankcase, a crank rotatable therein and a combustion chamber, the combination of means for admitting air and liquid fuel to said crankcase at low pressure, said means including means for adjusting the quantity of fuel in relation to the quantity of air admitted, sharp edged portions included in said crank, said crank with said sharp edged portions constituting a means, owing to its rotation, to break up said liquid fuel into particles and to mix the latter thoroughly with said air, and a conduit for said mixture from said case to said combustion chamber, said conduit being located between parts of the engine walls which receive heat from said combustion chamber.

7. A device for preparing an ignitable mixture for an internal combustion engine including a crank case, comprising interior roughened surfaces of said crank case, a vent in the crank case to admit air thereto, a duct connected to said crank case, to admit liquid fuel thereto, a movable member in said crank case, a driving means for said member to move it rapidly in said crank case, said member, owing to its rapid movement, being a means to vehemently agitate said air in said crank case, to break up said liquid fuel in particles, and to mix said particles thoroughly with said air, a second heated duct connected to said crank case to conduct quantities of said mixture to the combustion chamber of said engine, and means for varying the volume of said combustion chamber to a point where self-ignition of the mixture heated in said second duct occurs.
